UNITED STATES PATENT OFFICE

EDWIN M. WYATT, OF MADISON, WISCONSIN, ASSIGNOR, BY MESNE ASSIGNMENTS,
TO AMERICAN FACE BRICK RESEARCH CORPORATION, A CORPORATION OF ILLINOIS

METHOD OF TEXTURING FACE BRICK

Application filed December 14, 1928. Serial No. 326,011.

This invention pertains to means by which bricks can be textured on a fourth side when manufactured by the extrusion process.

In the process of manufacturing bricks by extruding the plastic clay through a die and then cutting the extruded column into individual bricks, the nature of the process is such that three sides only of the advancing column are presented to the comb or other texturing device which scores the plastic surface as the column advances in conformity with a well known treatment employed to increase the beauty of the resulting bricks. Many ways are known of imparting this texture by the use of some kind of abrading device, but heretofore, so far as I am aware, the use of such a device has been confined to the texturing of one, two or three of the normally exposed surfaces, which results in a brick having one of its long sides and both of its ends textured or ornamented in the manner stated.

No means have heretofore existed for texturing the surfaces made by cutting the column into unit bricks—usually the broad or four inch by eight inch face of a standard brick. In recently developed brick walls, some of the bricks are set to expose their broad faces in the wall surface. This method of laying some of the bricks on edge introduces a pleasing variety in the appearance of the wall, creates air spaces within that keep the interior dry and better insulated, and saves expensive material and labor.

The walls so far built with brick thus showing their broad faces have been constructed of untextured bricks generally known in the trade as "common bricks." Obviously, textured brick, generally called "face brick", cannot be used for such a wall unless the bricks are textured on at least one of the broad faces intended for exterior exposure. Heretofore no practical means have existed for thus texturing the broad faces of the bricks, and the object of my present invention is to provide a method whereby one of the broad faces, formed by cutting or severing the extruded column, may be textured in a manner conformable with the texturing commonly applied to three of the narrow edges of the brick.

In texturing brick by the ordinary method, it is the practice to extrude the uncut column from a die and to project it forwardly upon a traveling belt or apron and between combs or texturing devices which score the top and two sides of the uncut column, after which the advancing end of the column is cut or severed to the thickness of a brick, which presents the scoring on three of its edges.

In order to apply similar scoring or texturing to one of the broad faces, I provide means for upsetting the severed brick sections as they are advanced by the traveling apron or other conveying means, and thus present one of the recently cut surfaces upwardly in position to be scored by a supplemental scoring or texturing device, so that after the bricks have been fully textured on three edges and on one of the broad sides they will be delivered to be fired or otherwise completed.

More in detail, my method consists in extruding the plastic clay so as to form a continuous rectangular advancing column supported upon its under surface, texturing the advancing column on three sides while in uncut condition, severing the column into brick units, spacing the units somewhat from one another, upsetting the units to present one of the broad cut surfaces in parallel relation to the line of advance, bringing this freshly cut surface into contact with a texturing device, and afterwards heat treating the textured bricks to harden and strengthen the bricks and render them resistant to water.

In the drawings, I have shown in diagram various appliances adapted to carry out the method in question, although it will be understood that I do not limit myself to any particular form of mechanism, and that the devices as shown serve simply to exemplify various ways in which the method may be performed.

In the drawings:

Figure 1 is a perspective view of a wall section, showing intermediate courses laid to present their broad faces to the surface of the wall;

Fig. 2 is a perspective diagrammatic view illustrating a column of clay coming from

the die of a brick machine and passing through texturing devices including a device adapted to texture the bricks upon one of the broad severed surfaces;

5 Fig. 3 is a similar view, showing a modification in the method employed for upsetting the bricks; and

10 Figs. 4, 5 and 6 are diagrammatic views showing additional methods for upsetting the bricks to expose the broad surface to the action of the texturing device, it being understood that in Figs. 3, 4, 5 and 6 the die of the brick making machine is omitted.

15 Referring to Fig. 2, 1 illustrates the die of an extruding type of brick machine, from which issues the rectangular extruded column 2 of plastic clay, which is generally four by eight inches cross dimensions to conform to the length and breadth of a standard brick.

20 3 represents a simple texturing device which, as shown, is in the form of a three-part comb having teeth or prongs adapted to score the surface of the clay column as it is forced outwardly in uncut condition from the mouth 25 of the die. It will be understood, however, that the texturing device shown serves merely for purposes of illustration, since many different forms of device are employed in the art for texturing the exposed surfaces of 30 the clay column as it is forced outwardly from the mouth of the die. It will therefore be understood that the specific details of the texturing device shown form no portion 35 of the present invention, since various texturing devices may be employed in connection with the method herein described.

40 The textured portion of the advancing clay column, before it is cut into individual brick sections, is represented by the numeral 4, and the space marked at the point 5 is that occupied by a cutter, or cutting machine, of any suitable form or character well known in the art, which serves to cut the column into individual brick sections; and since the particular 45 form of the cutter constitutes no portion of the present invention, it is not deemed necessary to show or describe such a device, it being understood, however, that a suitable cutter of any well known type is to be located 50 at the point indicated.

55 The advancing uncut clay column is supported upon the upper turn of a belt 6, and after the sections are severed at the point 5 they are shoved forwardly along a sheet metal platen 7 being forced forwardly by the advancing column behind. In each of the drawings, the part 7 represents the platen referred to, and 8 represents the green bricks which have been textured along their narrow 60 faces after being cut and while still standing upwardly on their edges in the same relation in which the uncut column was extruded from the machine.

65 Referring now in particular to Fig. 2, the brick sections 8, advancing at the relatively

slow rate at which the column is extruded from the machine, are forced successively onto the upper turn of a more rapidly moving belt 9, which serves to suddenly draw or jerk away the outermost brick section from the 70 advancing column and overturn it onto one of its broad faces, with the other recently cut face exposed in position to be engaged by the supplementary texturing device 10, which thus scores the broad faces of the brick 75 sections in lines or grooves extending transversely of the previously formed lines or grooves on the edges of the brick sections. The speed of the conveyor belt 9 must be sufficiently accelerated with relation to the rate of travel of the extruding clay column so that the brick sections will not only be jerked forwardly and drawn down into flatwise relation, but will also be spread out sufficiently to clear one another so that their 80 upper surfaces will lie flush with one another in the same plane and thus be exposed evenly to the action of the texturing device. After the final texturing, the brick sections are carried forward to the point of delivery for 85 final firing or other treatment.

90 In the arrangement shown in Fig. 2, the forward edge of the platen 7 is preferably spaced from the upper turn of the belt a little less than the width of a brick, and the brick is upset by the action of the belt in pulling the bottom edge forwardly, which presents the previously upper edge to the rear as the brick takes its position upon the advancing belt.

95 In Fig. 3, a modified arrangement is shown, in which the platen 7a overhangs the belt 9, and is downturned at its forward edge to afford a slight offset which serves to upset the brick forwardly, instead of rearwardly as 100 in Fig. 2. In this case, also, it is necessary that the belt travel more rapidly than the extruding column, in order to properly space the upset bricks; but the actual upsetting is afforded, not as in Fig. 2 by the pull of the belt, but by the sliding off of the bricks at the down curved end of the stationary platen. In other respects the mechanism shown in 105 Fig. 2 is similar to that heretofore described.

110 In Fig. 4, the platen 7b is provided with a downturned lip 7c at its forward end, which causes the brick sections to fall forwardly onto the obliquely traveling turn of a belt 11 provided with spaced lugs 12 which afford 115 supports or carriers for the bricks which travel obliquely upward at this point and over a roller 13 which supports the horizontal upper turn of the belt which carries forward the bricks in spaced relation beneath a texturing 120 tool 10 similar to that heretofore described. In the case of Fig. 4 the speed of the belt should bear proper relation to the speed of the extruding column, so that a single brick 125 section will be delivered in timed relation to 130

each lug 12 as it goes into proximate relation to the lip 7.

In Fig. 5, the stationary platen 7^a aligns closely with the upper turn of a belt 9^a and terminates in close relation to it, so that the brick sections forced forwardly onto the belt will be carried forward by the more rapidly traveling belt, but continue standing on edge until their upper edges are engaged by a stationary finger 14 which upsets the brick sections rearwardly in proper relation to bring them under the texturing tool 10, which scores the exposed flat surfaces.

In Fig. 6, the forward end of the platen 7^b lies in closely adjacent relation to the upwardly lifting turn of a belt 9^b which passes over upper and lower rollers 15 and 16 respectively. This turn of the belt is in sagging relation, so that the bricks as they first pass onto the belt will be separated but continue to stand on edge until they approach the upper roller 16, at which point the slack of the belt is sufficient to upset the brick sections backwardly, after which they are carried over the roller and onto the flat upper turn of the belt in spaced relation and in position to be acted upon by the scoring tool.

Although the various mechanisms shown and described differ in details, they all provide means for spacing the brick sections and then upsetting them to present one of the broad faces to the action of the supplementary texturing tool. Proper provision must be made for the required spacing, in order to compensate for the greater space occupied by the brick sections when lying flatwise than when standing edgewise in the extruded column. While the various appliances conform in each instance to these requirements, it will be understood that other devices having a like capacity may be employed in the method and process of the present invention, and that it is not the intention to limit the practice thereof to any particular mechanism, since any adequate means, including manual manipulation, may be utilized to upset the bricks in preparation for the final scoring operation.

Although the drawings illustrate but one type of a very simple texturing device, it is to be understood that any kind of texturing apparatus adapted to act upon a brick section may be used in practicing the method of the present invention. Also, in the text, I have referred to what is generally called a four by eight clay column, which is of a size generally employed in the making of standard bricks, but it will be understood that the means for turning the bricks herein disclosed are to be considered as applicable to any size and shape of column suitable for the making of bricks or bricklike blocks, and it will be further understood that the fourth face textured after the upset of the brick sections is not necessarily the broad face, but that the

method herein described is intended to include the texturing of any face not previously exposed in the advancing column to the action of a texturing device. It will also be understood that minor changes and improvements not inconsistent with those heretofore disclosed may be employed without departing from the spirit of the invention.

I claim:

1. The method of making brick which comprises continuously extruding plastic material in the form of a plastic column supported upon its lower surface, texturing said plastic material upon an exposed surface of said column, cutting said column into units, turning said units to expose a cut surface of one of said units, conveying said units forwardly, and texturing said cut surface. 75

2. The method of making brick which comprises continuously extruding plastic material in the form of a plastic column supported upon its lower surface, texturing said plastic material upon an exposed surface of said column, cutting said column into units, turning said units to expose a cut surface of one of said units, conveying said units forwardly, texturing said surface, and heat treating said textured bricks to harden and strengthen and render said bricks water and heat resistant. 80

3. The method of making brick which comprises continuously extruding plastic clay in the form of a plastic column, supporting said plastic column upon its lower surface, texturing said plastic column upon an exposed surface, cutting said column into lengths, turning said lengths upon a cut surface, conveying said lengths in a forward direction, and texturing the other of said cut surfaces. 90

4. The method of making brick which comprises continuously extruding plastic clay in the form of a plastic column supporting said plastic column upon its lower surface, texturing said plastic column upon an exposed surface, cutting said column into lengths, turning said lengths upon a cut surface, conveying said lengths in a forward direction, texturing the other of said cut surfaces, and heat treating said textured bricks to harden, strengthen and render said brick water and heat resistant. 105

5. The method of making brick which comprises extruding plastic clay to form a continuous column, supporting said plastic column upon its lower surface, texturing said column upon its exposed surfaces, cutting said column into lengths, spacing said lengths from one another, texturing said lengths upon at least one of the cut surfaces, and finishing said lengths by a heat treatment. 120

6. The steps in the method of making brick which comprise supporting a column of plastic clay upon its lowermost surface, texturing said plastic column upon its exposed surfaces, cutting said column into lengths, and 130

texturing at least one of said cut surfaces.

7. The steps in the method of making brick which comprise supporting a column of plastic clay upon its lowermost surface, advancing said column into coacting relation with a texturing device to score its exposed surface, cutting said column into lengths, severally upsetting said unit lengths to expose the cut surfaces, accelerating the advance of said unit lengths to spread the same in flatwise relation and to expose the cut surfaces in a uniform plane, and bringing said surfaces into coacting relation with a texturing device.

15 8. The method of making brick which comprises continuously extruding plastic clay in the form of an advancing rectangular column, supporting said plastic column upon its lower surface, cutting said column into unit lengths, accelerating the speed of advance of said unit lengths and upsetting them in flatwise relation one behind another with their cut surfaces exposed, and bringing said cut surfaces into coacting relation with a texturing device.

25 9. The method of making brick which comprises continuously extruding plastic clay in the form of an advancing rectangular column, supporting said plastic column upon its lower surface, causing said column to coact with a texturing device to score an exposed surface thereof, cutting said column into unit lengths, accelerating the speed of advance of said unit lengths and upsetting them in flatwise relation one behind another with their cut surfaces exposed, and bring said cut surfaces into coacting relation with a texturing device.

30 10. The method of making brick which comprises continuously extruding plastic clay in the form of an advancing column, cutting said column into unit lengths, upsetting said unit lengths to expose the cut surfaces, and texturing said surfaces.

45 11. The method of making brick which comprises continuously extruding plastic clay in the form of an advancing rectangular column, supporting said plastic column upon its lower surface, cutting said column into unit lengths, and presenting said cut surfaces to the action of a texturing device.

In witness that I claim the foregoing I have hereunto subscribed my name this 26th day of November, 1928.

EDWIN M. WYATT.
